UNITED STATES PATENT OFFICE.

JOHN M. BROWNE, OF HOUSTON, TEXAS.

APPARATUS FOR TREATING PICKLES.

Application filed January 3, 1919. Serial No. 301,451.

To all whom it may concern:

Be it known that JOHN M. BROWNE, a citizen of the United States, residing at Houston, in the county of Harris and State 5 of Texas, has invented certain new and useful Improvements in an Apparatus for Treating Pickles, of which the following is a specification.

This invention relates to new and useful 10 improvements in an apparatus and process for treating pickles.

One object of the invention is to provide 15 an apparatus of the character described which has been specially designed for use in the treatment of pickles and particularly in extracting the salty brine from the pickles.

Another object of the invention relates 20 to a novel process of treating pickles and preparing the same for the market.

A further feature of the invention resides 25 in the provision of a simple and inexpensive apparatus for carrying out the process hereinafter described.

With the above and other objects in view, 30 the invention has particular relation to a novel process and to a novel apparatus the construction and operation of which is described in this specification and illustrated in the accompanying drawings, wherein:

Figure 1, shows a side elevation of the apparatus, and

Figure 2, shows a cross sectional view.

Referring now more particularly to the drawings wherein like numerals of reference designate similar parts in each of the figures, the numeral 1, refers to a cylindrical receptacle, fixed to one end of which there is the centrally located short shaft 2. 35 This shaft is rotatable in the gear 3, which is carried by one of the supporting legs 4, 4, and the outer end of the shaft 2 carries the band wheel 5, through which the shaft and the receptacle fixed thereon may be rotated from a suitable motor not shown. One side of the receptacle has the door 6 which is hinged thereto, and which may be secured in closed position by means of the clamp 7, in the usual manner. This door is provided 45 for filling and emptying the receptacle. Projecting inwardly from the wall of the receptacle are the lengthwise baffles 8 of any desired width, which are spaced apart around the receptacle. Entering the other

end of the receptacle, there is a steam pipe 55 9, whose inner end 10 is turned downwardly.

This pipe is supported by the other leg 4, and enters the receptacle through the centrally located end bearing 11 thereof, and forms a support for the corresponding end 60 of said receptacle.

The pickles to be treated are taken from the salty brine and placed in the receptacle which is filled with pure water and the receptacle is then rotated usually for a period of about twelve hours, until the salt is extracted therefrom, and the receptacle is then drained of the water and again filled with pure water. Steam is then forced in through the steam pipe which raises the 65 temperature of the water and the receptacle is then again rotated for a period of about twelve hours. The hot steam and water causes the pickles to expand and to absorb a considerable amount of the water, thus 70 increasing the pickles in bulk and permitting the further extraction of the remaining salt therein.

This treatment thus increases the size of each pickle and furthermore renders the 80 pickles tender and brittle, thus improving the quality and appearance and increasing the bulk thereof.

What I claim is:

An apparatus for treating pickles including a closed rotatably mounted cylindrical drum provided to contain brine, said drum having inwardly projecting baffles therein, a centrally located shaft fastened to one end thereof, a bearing in which said shaft rotates, a centrally located bearing carried by the other end of said drum, a support, a stationary steam pipe carried by said support and entering the drum through said last mentioned bearing and supporting the 90 adjacent end of the drum, the inner end of said steam pipe being turned downwardly and terminating in close proximity to the bottom of the drum so as to discharge steam into the brine at the bottom of the drum, 95 and a steam tight closure for said drum.

In testimony whereof he has signed his name to this specification in the presence of two subscribing witnesses.

JOHN M. BROWNE.
